UNITED STATES PATENT OFFICE

CARL P. KIONKA, OF CHICAGO, ILLINOIS, ASSIGNOR TO RICHARD L. PARISH, OF CHICAGO, ILLINOIS

BATTERY TERMINAL CONNECTER

Application filed June 11, 1928. Serial No. 284,450.

My invention relates to clamps adapted for use in connection with battery terminal connectors.

In accordance with my invention I cast the 5 ends of a split clamping ring about portions of a clamping bolt which portions have formations, inclusive of threads, of such nature that the bolt is inseparable from the ring and that when the bolt is rotated in one direction the ring is spread, and when rotated in the other direction the ring is contracted.

The invention will be more fully explained in connection with the accompanying drawings showing the preferred form of clamp 15 used in the construction of a battery terminal connector, Fig. 1 being a sectional view of the connector; Fig. 2 is a side view of the connector of Fig. 1, but showing it clamped upon a battery terminal; and Fig. 3 is a 20 longitudinal sectional view of the preferred form of bolt.

Referring now in detail to the drawings, the numeral 5 indicates a connecting cable which is usually constructed of copper wire 25 or copper strands and is covered with the insulating coating 6. My improved connector includes the body portion 7 preferably of lead or similar suitable acid resisting metal that will not corrode under the influence of 30 the fumes of the battery acid. The end 8 of the cable 5 may be moulded or otherwise secured in a recess 9 provided in the free end of the body 7. The body 7 as shown is provided with the annular portion 10 which is 35 adapted to extend around a battery post such as 11 shown in Fig. 2 and which has the free end portion 12 thereof extending back over the main portion of the body 7 which is cut away as at 13 to permit the end 12 to move 40 toward or away from the main body portion and decrease or increase the size of the aperture 14 in the annular portion 10.

It will be noted from Fig. 2 that this aperture 14 tapers inwardly from the upper and 45 lower faces 15 and 16 of the annular portion 10 being somewhat larger at the face 16 than at the face 15 and is provided with the substantially cylindrical portion 17 intermediate the two tapered portions. By making 50 the tapered portion adjacent the face 16

slightly larger than the tapered portion adjacent the face 15, the terminal may be made to fit posts of slightly different diameters by simply turning the connector over.

The adjusting member 18 by means of 55 which the connector is clamped on the battery post is a bolt having the screw threads 19 thereon engaging the interior screw threads 20 provided in an aperture in the end 12 of the connector. This bolt has the head 21 60 thereon and the shank portion thereof extends through the main body portion as at 22. The bolt 18 serves the dual function not only of drawing the clamp down upon the battery post by rotation of the bolt in one direction, but also of releasing the clamp from 65 the battery portion by rotating the bolt in the opposite direction. This is accomplished by mounting the bolt rotatably and non-slidably within the body portion 7 which is done 70 by providing the collars 23 and 24 on the bolt and corresponding annular recesses 25 and 26 in the portion 22 of the body 7 so that while the bolt 18 may rotate relative to the body 7 there can be no endwise movement of 75 the bolt relative to the body.

I accomplish this mounting by an improved method which requires no additional fastening means for preventing sliding of the bolt relative to the body. This method 80 consists primarily in casting the body 7 with the bolt 18 in position, that is, casting the body about the bolt 18 in the first instance rather than providing a hole through the body and subsequently inserting the bolt. 85

Heretofore, so far as I am aware, it has been the practice to cast these terminal connectors in a mold providing apertures through the portions 22 and 12 and subsequently threading the portion 12 to receive 90 the threaded end of the bolt 18. I found, however, that there is sufficient contracting of the metals as they cool after being cast to permit the casting of the lead body 7 about the bolt 18 after the bolt 18 has been threaded and the collars 23 and 24 provided thereon so that the bolt may be caused to turn relative to the body when cast in this fashion. 95

Thus, after the connector has been cast all 100 that is necessary to make the adjusting bolt

perform its function is to clamp the connector in a vise or other suitable molding device and by the use of a wrench to turn the bolt a few times relative to the body 5 when it becomes sufficiently loose to permit it to perform its adjusting functions with the connector. The interior threads on the portion 12 and the annular recesses 25 and 26 are by this method cast in the body 7 and the 10 terminal requires no machine work to finish it.

For preventing corrosion of the exposed portions of the bolt 18 I preferably plate the same with lead prior to casting it into the 15 connected body. This leaves the exposed portions of the bolt coated with lead after the connector is cast and makes a substantially acid proof terminal clamp. Moreover, since the amount of contraction of the metals 20 of the bolt 18 and the body 7 is quite small, a tight fit between them is assured by constructing the device in this manner.

From the above description of one form 25 of embodiment of my invention it is thought that the construction and advantages of this device will be clear to those skilled in this art and having thus described my invention what I claim as new and desire to secure by Letters Patent is:

30 1. A battery terminal connector comprising a split ring, a bolt, said ring having its ends cast about portions of the bolt, the bolt having threads on one of said portions intimately contacting with internal threads 35 within one end of the ring and having formations on the other of said portions embedded in the other end of the ring by casting and rotatably connected therewith, said bolt being retained in inseparable relation 40 with the ring and rotatable in one direction to spread the ring and rotatable in the other direction to contract the ring, the formations coacting with one end of the ring to cause the threads to move the other end of the ring.

45 2. A battery terminal connector comprising a split ring, a bolt, said ring having its ends cast about portions of the bolt, the bolt having threads on one of said portions intimately contacting with internal threads 50 within one end of the ring and having circumferentially extending ribs on the other of said portions embedded in the other end of the ring by casting, said bolt being retained in inseparable relation with the ring and rotatable in one direction to spread the ring and rotatable in the other direction to contract the ring, the ribs rotatably connected with one end of the ring to cause the threads to move the other end of the ring.

55 3. A battery terminal connector comprising a cast member including a split ring, a unitary bolt, said bolt being provided with formations, said ring having its ends cast about the formations of the bolt whereby said 60 formations are embedded in and intimately

contact with interacting complementary formations within the ends of the ring to secure the bolt inseparably from the ends of the ring and whereby said bolt is rotatable therein in one direction to cause spreading of the ring and rotatable in the other direction to cause contraction of the ring.

In witness whereof, I hereunto subscribe my name this 15th day of May, A. D. 1928.
